UNITED STATES PATENT OFFICE.

CHARLES C. BLAKE, OF BROOKLINE, MASSACHUSETTS, ASSIGNOR TO C. C. BLAKE, INCORPORATED, OF BOSTON, MASSACHUSETTS, A CORPORATION OF NEW YORK.

SEAM.

Application filed November 6, 1920. Serial No. 422,278.

The present invention relates to the art of making seams such, for instance, as the outseam of a shoe.

Usually an outseam for a shoe comprises a lock stitch which to make requires the use of two threads which are fed to the work from a source of supply located above and below the work, respectively. One of the sources of thread supply is placed in a shuttle and to perfect the lock in the two threads it is necessary to draw from the other thread supply a long length of thread so that when it is drawn through the parts to be stitched it may be passed in a loop completely about the shuttle. Consequently, the thread comprising the loop must be drawn repeatedly through the work and this reaving of the thread weakens it.

The object of the present invention is to provide a novel method of making a seam having utility in the manufacture of shoes, harness, etc. whereby the use of a shuttle or two sources of thread supply is obviated.

To the accomplishment of this object, and such others as may hereinafter appear, the features of the invention relate to certain devices, combinations, arrangements of parts, and methods of manufacture hereinafter described, and then set forth broadly and in detail in the appended claims, which possess advantages readily apparent to those skilled in the art.

The various features of the present invention will be best understood from an inspection of the accompanying drawings illustrating the best form of the invention at present devised in which,

Figure 1 is a detail in sectional elevation showing the application of the invention to the manufacture of shoes. As shown, the upper, welt and insole are secured together by a thread passing through the welt and anchored about a post formed in the body portion of the insole. The outsole is secured to the welt by a line of thread passing through the welt and anchored about a post formed in the body portion of the outsole;

Fig. 2 is a detail, partly in sectional elevation, showing the gouge which forms the post in the work and a doubled thread passed through the parts to be stitched;

Fig. 3 is a view similar to Fig. 2 but showing how the gouge operates to pass the thread about the post;

Fig. 4 is a view similar to Figs. 2 and 3

showing the position of the thread after it has been passed about the post and about to be taken up;

Fig. 5 is a detail in plan showing the seam;

Fig. 6 is a detail in sectional elevation of the seam shown in Fig. 5; and

Fig. 7 is a perspective of the combined gouge and looper for forming the stitch anchoring post and looping the thread about the post

Referring to Fig. 1, the upper 1, welt 2 and insole 3 are secured together by a line of thread 4 which is fastened to the base of a slit 5 formed in the welt 2 and anchored about a post 6 formed in the insole. The outsole 7 is secured to the welt 2 by a line of thread 8 passing through the welt and anchored about a post 9 formed in the outsole.

In order to form the stitch anchoring posts in the work, I have devised the combined gouge and looper 10 illustrated in Fig. 7. This device is hollow for a portion of its length and terminates in a cutting edge 11 so that when the gouge is driven into the work it forms the stitch anchoring post. This post, as shown most clearly in Figs. 1 and 6, extends from the interior of the gouged part to the surface thereof and is connected to the gouged part at its base only.

The combined gouge and looper 10 is also provided with a longitudinal channel 12 bordered by a pair of wings 13 and 14. The wing 13 is longer than the wing 14 by an amount substantially equal to the thickness of the thread. The wing 14 is also provided with a rounded corner 15.

In order to stitch two parts such as 16 and 17, (Figs. 2, 3 and 4) together, the gouge 10 is driven into the work to a depth limited by the shoulder 18 (Fig. 7), to form the stitch anchoring post 19. Simultaneously with the formation of the stitch anchoring post, or in any suitable or desirable sequence, a doubled thread 20 is drawn through the parts 16 and 17 and located between the wings 13 and 14 (Fig. 2). The thread 20

may be drawn through the parts to be stitched by an ordinary hooked needle and this operation may be preceded by an awling operation to form the holes for the passage of the thread.

After the thread has been passed through the work as shown in Fig. 2 the combined

gouge and looper 10 is rotated in a counter clockwise direction. During the rotation of the gouge the wing 13 expands the space around the post and the rounded corner 15 on the wing 14 steps on the thread and lays it down in the bottom of the gouge hole.

During the rotation of the gouge no tension is placed upon the line of thread coming from the source of thread supply but as soon as a single rotation of the gouge has been completed the thread is taken up first to draw it tightly against the exterior of the gouge, and then, upon the removal of the gouge, to draw it tightly in place about the post adjacent the base thereof.

It will be apparent to those skilled in the art and from an inspection of Figs. 5 and 6 that the combined gouge and looper 10 is transferred in a step by step manner along or around the work and that the steps of the method hereinbefore described are repeated in succession until the seam is completed.

What is claimed as new is:

1. In combination, two members, one of which is provided with integral posts connected to the member within the body portion thereof only at a substantial distance from the surfaces of the member, and both of which are provided with a thread passed through both of the members and looped about the posts.

2. In combination, two members one of which is provided with stitch anchoring posts connected at their bases only within the body portion of the member at a substantial distance from the surfaces thereof, and both of which are provided with a thread secured to one of the members and looped about the posts on the other member.

3. In combination, two members one of which is provided with integral posts formed in the member and completely separated from the adjacent face of the member, and both of which are provided with a thread passed through both of the members and looped about the posts.

4. In combination, two members one of which is provided with integral posts formed in the member and rising clear of the member from the interior thereof, and both of which are provided with holes whereby a thread passed through the holes may be looped about the posts.

5. A welt shoe having, in combination, an upper, a welt and an insole provided with cylindrical posts integral therewith separated from the adjacent surface of the insole, secured together by a line of thread passing through the welt and upper and anchored about the posts formed in the insole.

6. A welt shoe, having, in combination, an upper, a welt and an insole provided with stitch-anchoring devices integral therewith completely separated from the adjacent face of the insole secured together by a line of

thread passing through the welt and anchored about the stitch anchoring devices.

7. A shoe, having, in combination, an unchannelled outsole provided with cylindrical posts separated from the adjacent surface thereof and a part to which the outsole is secured by a line of thread passing through the part and looped about the posts.

8. In combination, two members, one of which is provided with a series of cylindrical posts secured at their bases only to the member and separated from the adjacent surface thereof, and both of which are provided with a thread passing into the members and looped about the posts.

9. A shoe, having in combination, an unchannelled outsole provided with stitch-anchoring devices formed in the material of the outsole and separated from the adjacent surface thereof, and a part to which the outsole is secured by a line of thread passing through the part and looped about stitch anchoring devices formed in the outsole.

10. A welt shoe, having in combination, an upper, a welt and an insole secured together by a line of thread passing through the welt and anchored, entirely below the surface of the insole, to a stitch anchoring device formed integral with the insole.

11. A welt shoe, having in combination, an upper, a welt slit along one longitudinal edge to provide an interior shoulder, an insole provided with a post, and means for securing the upper, welt and insole together comprising a thread engaging the interior shoulder of the welt and looped about the post in the same plane as the slit in the welt.

12. That improvement in the art of making seams which consists in forming a cylindrical post in one of the parts to be stitched entirely separated from the adjacent surface thereof, passing a doubled thread through both of the parts to be stitched, and looping the thread about the post.

13. That improvement in the art of making seams which consists in gouging one of the parts to be stitched to form a post connected at its base only to the interior of the gouged part, passing a doubled thread through both of the parts to be stitched, and looping the thread about the post.

14. That improvement in the art of making seams which consists in gouging one of the parts to be sewn to form a post connected at its base only to the interior of the gouged part, passing a loop of thread into both of the parts to be sewn, and laying a thread down in the bottom of the gouge hole around the post.

15. That improvement in the art of making seams which consists in forming a cylindrical stitch anchoring device in one of the parts to be stitched, passing a doubled thread through both of the parts to be

stitched, expanding the space surrounding the stitch anchoring device and laying the thread about the stitch anchoring device.

16. That improvement in the art of making seams which consists in forming a cylindrical stitch anchoring device in one of the parts to be stitched, passing a doubled thread through both of the parts to be stitched, expanding the space surrounding the stitch anchoring device, laying the thread about the stitch anchoring device adjacent the base thereof and taking up the stitch.

17. That improvement in the art of making seams which consists in gouging one of

the parts to be sewn to form a post connected at its base only to the interior of the gouged part, passing a loop of thread through both of the parts to be sewn, and running the loop of thread around the post. 20

18. That improvement in the art of making seams which consists in gouging one of the parts to be sewn to form a post connected at its base only to the interior of the gouged part, passing a loop of thread into both of the parts to be sewn, and progressively extending the loop about the post. 25

In testimony whereof I have signed my name to this specification.

CHARLES C. BLAKE.
